PIN-ON CONTAINER FOR SEWING ACCESSORIES

Mary C. Millis, 5310 Morningside, Dallas, Tex.

Filed Mar. 23, 1959, Ser. No. 55,123

Term of patent 14 years

(Cl. D3—21)

I claim:

The ornamental design for a pin-on container for sewing accessories, substantially as shown.
